[57] CLAIM

The ornamental design for combined outdoor floodlight
unit and photo electric control therefor, as shown and
described.

DESCRIPTION

FIG. 1 is a front elevational view of a combined outdoor
floodlight unit and a photo electric control therefor showing my new design;

FIG. 2 is a top plan view thereof;

FIG. 3 is a rear elevational view thereof;

FIG. 4 is a bottom plan view thereof; and

FIG. 5 is a right side elevational view, the left side being
a mirror image.

FIG. 1**FIG. 2****FIG. 3**FIG. 4

FIG. 5
